UNITED STATES PATENT OFFICE.

NEWTON C. SPRAGUE, OF MINNEAPOLIS, MINNESOTA, ASSIGNOR TO M. W. SAVAGE, OF MINNEAPOLIS, MINNESOTA.

BROODER.

No. 846,155.

Specification of Letters Patent.

Patented March 5, 1907.

Application filed January 29, 1906. Serial No. 298,303.

To all whom it may concern:

Be it known that I, NEWTON C. SPRAGUE, of Minneapolis, Hennepin county, Minnesota, have invented certain new and useful 5 Improvements in Brooders, of which the following is a specification.

The object of my invention is to provide a brooder which is capable of being taken apart readily for cleansing purposes or repairs.

10 A further object is to provide a brooder in which it will be impossible for the chicken to come in direct contact with a heated surface.

15 A further object is to provide a brooder in which the circulation of pure warm air through the hover is positively insured.

Other objects of the invention will appear from the following detailed description.

20 The invention consists generally in various constructions and combinations, as is hereinafter described, and particularly pointed out in the claims.

25 In the accompanying drawings, forming part of this specification, Figure 1 is a perspective view of a brooder embodying my invention. Fig. 2 is a transverse vertical sectional view of the same.

In the drawing, 2 represents the walls of 30 the brooder supported upon suitable legs 3 and having a removable cover 4.

35 5 is the bottom of the brooder, having a central opening 6, over which a drum 7, preferably cylindrical in form, is removably arranged on a flange 6'. The walls of this drum at the top have a series of holes 7', and the top of the drum 7 has a cap or dome 8, on which a circular plate 9, forming the top of the hover, is centrally resting upon clips 10, provided on the top of the drum. The plate 9 has suitable exhaust-holes 11, communicating 40 with the interior of the brooder, and a flexible curtain 12 is suspended from the said plate and depends to a point near the floor of the brooder and is provided with a series of slits 13 to facilitate the passage of the chickens from the brooder-chamber to the space within the hover. The cover 4 is provided with suitable exhaust-openings 14, through which the foul air is discharged.

Beneath the floor 5 is a plate 15, and between said plate and floor are flues 16, communicating with the interior of the drum 7 and with the open air through ports 17 in said plate. The cool air entering the ports

17 flows up around and through the drum and the perforations therein into the space 55 inclosed by the hover-curtain. A flange 18 is mounted on the plate 15 and supports an imperforate drum 19, which projects up into the drum 7 and is spaced from the walls thereof. The drum 19 is accessible after the 60 drum 7 is removed and may also be detached for convenience in cleaning. A pipe 20 is carried by the plate 15 and extends up into the drum 19 and has an open upper end communicating with the interior of said drum, 65 and an open lower end, into which the heating-lamp 21 is inserted. This lamp is mounted on a suitable track or guide 22 and is adapted to be slipped in under the pipe 20, being limited in its movement by a stop 23, 70 so that no accurate adjustment of the lamp is required, it being merely necessary to push it on the track as far as it will go. The lower end of the pipe 20 has a cut-out portion 24 to permit the passage of the lamp. 75

A flue 25 communicates with the space inclosed by the lamp 21 and the drum 19 and leads out between the plate 15 and the floor of the brooder to the open air. The heat of the lamp will create a circulation through the 80 pipe 20 and the drum 19 and out through the discharge-flue, and the cool air entering the space between the drums 7 and 19 will be warmed by contact with the latter drum and will pass out through the perforations in the 85 drum 7 to the chicken-hover. A circulation of pure air through the hover and brooder is thus obtained, and the heat will be evenly distributed and constantly maintained at all points. The floor of the brooder will not be 90 hot—an objection to many styles of brooders—and as the outer drum cannot become hot it will be impossible for the chickens to be injured through contact with a hot radiating-surface. The circulation of air between the 95 drums can be regulated so that the desired temperature can be obtained in the brooder and a perfect system of heating and ventilating secured.

Whenever desired, the cover of the brooder 100 may be removed, the hover-plate 9 lifted, and convenient access had to the drums for the purpose of cleaning off the soot which will accumulate thereon.

I claim as my invention—

1. In a brooder, the combination, with a 105

casing having a floor provided with an opening therein, of a perforate drum mounted on said floor over said opening and spaced from the top of the brooder, a hover-plate supported above said drum and spaced from the top and side walls of the brooder, a curtain supported on said hover-plate and inclosing said drum, an imperforate drum arranged within the opening in said floor and spaced from the walls and top of said first-named drum and having an exhaust or foul-air flue, means supporting said imperforate drum, a pipe extending up into said imperforate drum, a lamp arranged beneath said pipe and said perforate drum having a cold-air-intake flue and said hover-plate having exhaust-openings, and said drums being separable and removable from their supports to facilitate the cleaning of their interior surfaces, substantially as described.

2. In a brooder, the combination, with a casing having a floor provided with an opening therein and a flange surrounding the same, of a drum having a closed top and perforate side walls and an open bottom fitting over said flange, a hover-plate supported above said drum and spaced from the top of the brooder and the side walls thereof and having a curtain inclosing said drum, a plate arranged beneath the floor of the brooder, a second flange mounted on said plate beneath the opening in said floor, an imperforate drum fitting on said second flange and extending up through the opening in said floor into said first-named drum and spaced therefrom, and said perforate drum having a cold-air inlet and said imperforate drum having a foul-air-exhaust, a pipe projecting up through said plate into said imperforate drum and a lamp arranged beneath said pipe and said drums being removably mounted on said

flanges, whereby access may be had to their interior surfaces for cleaning purposes.

3. In a brooder, the combination, with a casing having a floor provided with an opening therein and a flange inclosing said opening, of a perforate drum removably mounted on said flange, a plate arranged beneath said floor, a second flange thereon beneath the opening in said floor, an imperforate drum removably mounted on said second flange and projecting up through said opening into said perforate drum and spaced from the walls thereof, said perforate drum having a cold-air-intake opening, and said imperforate drum having a foul-air-exhaust flue, a pipe projecting up into said imperforate drum, and a lamp arranged beneath said pipe.

4. The combination, with a brooder-casing having a floor provided with an opening therein, of a perforate drum arranged over said opening, clips provided on the top of said drum, a hover-plate resting upon said clips and spaced from the top of the brooder and having exhaust-openings and a curtain inclosing said drum, an imperforate drum projecting up into said first-named drum through the hole in said floor, means supporting said imperforate drum, a plate whereon said imperforate drum is supported, said perforate drum having a cold-air-intake flue, and said imperforate drum having an exhaust-flue, a pipe supported in said plate and projecting up into said imperforate drum, and a lamp arranged beneath said pipe.

In witness whereof I have hereunto set my hand this 19th day of January, 1906.

NEWTON C. SPRAGUE.
